Attorney

UNITED STATES PATENT OFFICE.

WALTER R. BENNETT, OF FORT WORTH, TEXAS.

BUILDING-TILE.

1,289,367.

Specification of Letters Patent. Patented Dec. 31, 1918.

Application filed October 18, 1917. Serial No. 197,358.

To all whom it may concern:

Be it known that I, WALTER R. BENNETT, a citizen of the United States of America, residing at Fort Worth, in the county of 5 Tarrant and State of Texas, have invented certain new and useful Improvements in Building-Tiles, of which the following is a specification.

My invention relates to tile or building 10 blocks and more particularly to hollow blocks or tile and hollow corner blocks, and the object is to provide blocks which will prevent moisture from passing through the walls. One of the objects is to provide 15 blocks or tile which will make air spaces or vacancies in the wall to prevent the passage of moisture or water and to provide corner blocks in which there will be sufficient air spaces or vacancies to prevent the passage 20 of moisture or water and which will form a means for tying the walls securely and which will provide the necessary strength. Other objects and advantages will be to provide blocks which can be easily made or 25 manufactured and which will not be expensive to manufacture. Reference is had to the accompanying drawings which form a part of this application.

Figure 1 is a plan view of several blocks 30 arranged as in a wall. Fig. 2 is an elevation of the same, showing the lowest block in section. Fig. 3 is a perspective view of one of the main wall blocks. Fig. 4 is a plan view of one of the corner blocks. Fig. 5 is a 35 plan view of two corner blocks assembled. Fig. 6 is a perspective view of several blocks assembled as forming part of the corner wall of a building. Fig. 7 is an end view of a block, showing a variation. Fig. 8 is a 40 plan view of a corner block, showing a variation.

Similar characters of reference are used to indicate the same parts throughout the several views.

45 The improved blocks are simple in construction and two or three forms of blocks are all that are necessary in the construction of the building. The blocks 1 are of tongue and groove construction, having a 50 groove 2 in the lower side and a tongue 3 on the upper side, the tongue fitting into the groove of the block next above. Each block 1 has a central air space 4 and lateral air spaces 5 so that no moisture or water can 55 pass through the wall without coming into an air space or more than one air space. The

blocks 1 are so arranged or placed in the wall that the wings or webs of one block are vertically in line with the blocks below and above. The pressure is thus on the strong 60 parts of the blocks. The wings of the blocks are connected by the webs 7 and the arches 8. The corner or locking blocks 9 have grooves 10 to receive parts of tongues 3. The wings 11 of the corner blocks will be 65 alternately arranged, that is, the wings 11 of one block will receive a tongue 3 of a block on one side and the wings 11 of the next block above or below will receive the tongue of a block on the other or adjacent 70 side of the wall. The blocks 9 are provided with vertical openings 12 and 13 and when block 9 is placed upon another block 9, as shown in Figs. 1 and 5, no moisture can pass through any part of the corner without coming to an air space. When the moisture comes to an air space, it stops and will not go farther through the wall. The wings 11 of the corner blocks 9 will be locked between the wings or webs 6 of the blocks 1 and the 75 corner blocks will be locked against lateral movement by the tongues 3 and the corner blocks will lock the side and end walls against lateral movement by reason of the wings 11 engaging the tongues of the side 80 wall blocks. Air space is left above the tongues 3, between the upper sides of the tongues and the upper walls of the grooves 2. The mortar joints 15 are shown exaggerated for clearness in illustration. Air spaces 90 will also be left between the meeting faces of blocks. It is a well known practice with masons that mortar is placed only on the edges of tile so that there will be more or less air space between the blocks which will 95 be entirely inclosed by the mortar and the blocks.

The variation shown in Fig. 7 includes two ribs 16 instead of one rib or tongue, as shown in previous views, and a corresponding increase in the number of horizontal openings. Fig. 8 shows a corner block with an additional vertical opening and with an additional vertical groove to be used with such blocks as are shown in Fig. 7.

100 The blocks make it possible to build walls with the greatest possible strength which are provided with ample air spaces to prevent the passage of moisture or water through the walls. The corner tie blocks 110 provide for closing the corners without the expensive sealing heretofore practised. The

blocks are closed on the outer ends and the inner ends are prepared for interlocking with the blocks which form the walls and at the same time the blocks eliminate the trouble of moisture penetrating the walls.

What I claim, is,—

1. A wall composed of horizontally disposed blocks having longitudinal grooves in their lower sides and longitudinal tongues 10 on their upper sides for interlocking with each other and having pluralities of longitudinal openings therethrough, and corner tie blocks substantially U-shaped, being closed at one end and having vertical grooves in 15 the other ends, said tie blocks being alternately arranged for receiving in said vertical grooves portions of the tongues of alternate layers of said horizontally disposed blocks and each block having pluralities of 20 vertical openings therethrough for intercepting mortar joints and for forming communicating air spaces with each other for preventing the passage of moisture through the wall.
- 25 2. A wall composed of horizontally disposed blocks having interlocking tongues and grooves and pluralities of longitudinal openings therethrough, and corner tie blocks

substantially U-shaped, being closed at one end and having vertical grooves in the other 30 ends and alternately arranged to receive portions of the tongues of alternate layers of said horizontally disposed blocks and having pluralities of vertical openings communicating with openings of alternate 35 blocks and communicating with the openings in said horizontal blocks for intercepting all mortar joints for preventing moisture from passing through the walls.

3. A wall composed of horizontally disposed hollow blocks having interlocking horizontal tongues and grooves and substantially U-shaped corner tie blocks closed on their outer ends and having relatively long vertical grooves in their inner ends and said 40 corner blocks being alternately arranged for receiving in their grooves portions of the tongues of alternate layers of said horizontally disposed blocks, said corner blocks having communicating vertical openings for 45 forming air spaces to prevent the passage of moisture through the wall.

In testimony whereof, I set my hand, this 10th day of October, 1917.

WALTER R. BENNETT.
